DRY LAND CHISEL TILLER BLADE

Roy I. Hawkins, Pierce, Colo.

Filed Sept. 14, 1964, Ser. No. 81,699

Term of patent 14 years

(Cl. D35—2)

Fig. 3

FIG. 1 is a top plan view of a dry land chisel tiller blade showing my new design;

FIG. 2 is a perspective view of the design of the chisel blade as would appear when looking obliquely on the lines 2 in the direction of the arrows of FIG. 1;

FIG. 3 is a side elevational view of the unit shown at FIG. 1, taken on the line 3 and looking in the direction of the arrow;

FIG. 4 is a cross-sectional view taken on the line 4—4 of FIG. 2 looking in the direction of the arrows.

The undisclosed rear portion of the blade is unornamented.

I claim:

The ornamental design for a dry land chisel tiller blade, as shown and described.
